UNITED STATES PATENT OFFICE.

ROBERT THALER, OF BAY CITY, MICHIGAN.

PROPELLER-WHEEL.

No. 906,337.

Specification of Letters Patent.

Patented Dec. 8, 1908.

Application filed January 16, 1908. Serial No. 411,126.

To all whom it may concern:

Be it known that I, ROBERT THALER, a subject of the German Empire, residing at Bay City, in the county of Bay and State of Michigan, have invented certain new and useful Improvements in Propeller-Wheels; and I do hereby declare the following to be a full, clear, and exact description of the invention, such as will enable others skilled in the art to which it appertains to make and use the same.

My invention relates to propeller wheels, one object of which is to provide a propeller, the outer ends of the blades of which will always run in solid water.

Another object of my invention is to provide means to absolutely prevent either endwise or rotatable movement of the propeller relative to the propeller shaft.

To these ends my invention consists in certain novel features and combinations, such as will be more fully pointed out hereinafter and particularly referred to in the claims.

In the drawings, Figure 1 is a cross-sectional view through the hub of my propeller applied to the shaft; Fig. 2 is a view in side elevation of the shaft alone; Fig. 3 is a cross-sectional view through the propeller hub; and Fig. 4 is an end view of the propeller hub, the blades being broken away.

In former constructions of propeller hubs and shafts, it has been very difficult to provide a connection between the hubs and the shafts which would prevent the propeller from ultimately wabbling relative to the shaft. Furthermore, in former constructions having a tapering shaft on which the hub of the propeller is driven and held by means of a lock nut, it is very difficult to remove the hub in case one of the blades is broken.

Referring to the drawings, (A) indicates the propeller shaft, the rear end of which is tapered, as shown at (1), and provided with keys (2) (2) inclined from the tapered end of the shaft, the keys finally merging into the periphery of the shaft (A). These keys are located about equidistant from each other.

The bore of the hub (B) is tapered from end to end, the bore being provided with longitudinally-extending channels or keyways (3) (3), which ways gradually increase in depth from end to end of the bore, finally merging into the bore of the hub at its inner larger end. The parallel key-ways operate to divide the bore of the hub into several ribs (4) (4), which, owing to the taper

of the bore of the hub, are wider at their forward ends than at their rear ends, their forward ends merging into the inner periphery of the hub. The rear ends of these ribs are cut away and do not extend to the rear end of the hub, but constitute a seat for a suitable screw or fastening (5), which is screwed into the rear end of the propeller shaft after the latter is inserted into the hub of the propeller, the screw extending longitudinally of the shaft and by its engagement with the ends of the ribs (4) operates to force the propeller hub endwise onto the propeller shaft, the keys (2) (2) of the shaft being received in the key-ways (3) (3) in the hub, the ribs (4) (4) of the hub being received in the spaces between the keys (2) (2) of the shaft. The taper of the shaft and of the bore of the hub are substantially similar so that a snug fit is produced and it will be seen that by reason of the interlocking keys (2) (2) on the shaft and the ribs (4) (4) on the hub of the propeller, movement of the shaft and hub relative to each other is prevented. Further than that, the engagement of the screw (5) carried by the shaft with the ends of the ribs (4) (4) of the hub absolutely prevents endwise movement of the hub relative to the shaft, and affords a very easy and convenient means for removing the propeller from the shaft when necessary.

In all former propellers with which I am familiar, the blades extend rearwardly so that the hub engages the water first and breaks it up before the blade. Thus the blades work in broken water and do not impart so much propelling force to the vessel as they would if they engaged solid water.

It is well recognized that the majority of the work done in propelling a vessel is derived from the end of the blade, which exercises the greatest leverage against the water. Therefore, I incline the blades (6) of my propeller forwardly toward the boat in advance of the hub so that the outer ends of the blades engage the solid water first before it is broken up by the hub.

Having thus fully disclosed my invention, what I claim as new is—

1. A propeller shaft having a tapered end, longitudinally-extending wedge-shaped keys on the tapered end of the shaft, the forward ends of the keys merging into the shaft, a propeller hub, the bore of which is tapered, the inner periphery of the hub provided

with channels, the forward ends of which merge into the bore, wedge-shaped ribs in the bore of the hub, the ribs received between the keys on the shaft, the keys lying in the channels in the bore, and means carried by the shaft and engaging the hub to prevent movement of the hub longitudinally of the shaft.

2. The combination of a propeller hub, 10 the bore of which is tapered from end to end and is provided with channels whose ends merge into the larger end of the bore, a shaft tapered at one end, keys on the tapered end, the keys at one end merging into the shaft, and means for securing the shaft and hub against relative longitudinal movement.

3. The combination of a propeller hub, 20 wedge-shaped ribs spread apart from each other in the bore of the hub, a tapered shaft, keys carried by the tapered shaft and received between the ribs in the bore, the keys merging at one end into the shaft, and means for preventing endwise movement of 25 the hub relative to the shaft.

4. The combination of a propeller hub, wedge-shaped ribs spaced apart from each other in the bore of the hub, a shaft having a tapered end, wedge-shaped keys on the 30 tapered end of the shaft, the keys received between the ribs of the bore, the ribs at one end merging into the bore of the hub, the keys at one end merging into the periphery of the shaft, and means for preventing end- 35 wise movement of the hub relative to the shaft.

5. The combination of a propeller hub, wedge-shaped ribs spaced apart from each other and extending longitudinally of the 40 hub, the inner ends of the ribs merging into the bore of the hub, the outer ends of the ribs being cut away, a shaft having a tapered end received in the hub, keys carried on the tapered end and received in the spaces be- 45 tween the ribs, the ribs snugly fitting the

tapered end of the shaft between the keys, and a fastening means carried by the shaft and engaging the outer ends of the ribs.

6. The combination with a propeller shaft 50 tapered at its outer end, of raised keys extending longitudinally of the tapered end, the inner ends of the keys merging into the shaft, a propeller comprising a hub and blades, the hub having a tapered bore, in which are formed longitudinally extending 55 key ways, merging at their inner ends into the bore of the hub, ribs separating the key ways, the ribs being widest at their inner ends and merging into the bore of the hub, the keys received in the key ways, the ribs received in the spaces between each two adjacent keys and means carried by the outer end of the shaft and countersunk in the bore 60 of the hub for securing the hub against longitudinal movement relative to the shaft. 65

7. A propeller mechanism comprising a shaft tapered at its outer end, keys on the tapered end, a propeller hub, the bore of which is tapered, and provided with key 70 ways, the inner ends of which merge into the bore of the hub, and a fastening means carried by the outer end of the shaft and engaging the hub.

8. A propeller mechanism comprising a shaft tapered at its outer end, keys on the 75 tapered end, a propeller hub, the bore of which is tapered, and provided with key ways, the inner ends of which merge into the bore of the hub, ribs located between each two key ways, and a fastening means carried 80 by the outer end of the shaft and countersunk in the bore of the hub to retain the latter on the shaft.

In testimony whereof, I affix my signature in presence of two witnesses.

ROBERT THALER.
